Des. 238,713
Patented Feb. 3, 1976

238,713

FRONT PANEL FOR A MEDICAL INFUSION PUMP

Sydney Hudspith, San Diego, Calif., assignor to Imed Corporation, San Diego, Calif.

Filed Aug. 10, 1973, Ser. No. 387,440

Term of patent 14 years

Int. Cl. D24—02

U.S. Cl. D83—1 F

The figure is a perspective view of a front panel for a medical infusion pump showing my new design. The undisclosed side is the same as the side shown and the bottom and rear are substantially flat and unornamented.

I claim:

The ornamental design for a front panel for a medical infusion pump, as shown and described.
